E. T. SLOUGH, DEC'D.

J. F. DEVINE, ADMINISTRATOR.

VALVE.

APPLICATION FILED AUG. 24, 1908.

950,464.

Patented Feb. 22, 1910.

UNITED STATES PATENT OFFICE.

JOHN F. DEVINE, OF CHICAGO, ILLINOIS, ADMINISTRATOR OF EDWARD T. SLOUGH,
DECEASED, ASSIGNOR TO ELIZABETH SLOUGH, OF DELAWARE, OHIO.

VALVE.

950,464.

Specification of Letters Patent. Patented Feb. 22, 1910.

Application filed August 24, 1908. Serial No. 449,947.

To all whom it may concern:

Be it known that I, JOHN F. DEVINE, a citizen of the United States, residing at Chicago, county of Cook, and State of Illinois, administrator of the estate of EDWARD T. SLOUGH, formerly of Chicago, Illinois, deceased, respectfully make known and declare that said EDWARD T. SLOUGH in his lifetime invented certain new and useful 10 Improvements in Valves, of which the following is declared to be a full, clear, and exact description.

The invention relates to valves for controlling the flow of fluid under pressure and 15 more particularly to manually operated valves for controlling the flow of liquid under pressure to and from a motor cylinder.

The invention seeks to provide a simple and effective form of valve which will be 20 balanced and therefore easily operable.

Further objects of the invention are to obviate the necessity of employing stuffing boxes and the like.

With these and other objects in view, the 25 invention consists in the features of construction, combinations and arrangements of parts hereinafter set forth, illustrated in the accompanying drawings and more particularly pointed out in the appended claims.

30 In the drawings, Figure 1 is a longitudinal section showing an embodiment of the present invention. Fig. 2 is a detail section on line 2—2 of Fig. 1. Fig. 3 is an end view of parts shown in Fig. 1.

35 The embodiment of the invention selected for illustration is a form of hand-operated valve designed for controlling the flow of air, steam or any suitable liquid under pressure to and from a motor cylinder, such as 40 that of an air, steam or hydraulic hammer, press or the like, but it will be understood that the improved valve may be adapted for numerous other uses.

The casing 1 of the valve in the form 45 shown, is secured by bolts 2 to a boss or projection 3 in the side of the engine cylinder 4. A rotary valve 5 is axially arranged within the bore of the valve casing, the main body of the valve being spaced apart as shown, 50 from the walls of the bore or valve chamber in the casing. One of these parts is provided with end flanges and an intermediate flange which fit the other of said parts to form inlet and exhaust members 6 and 7 55 within the bore of the valve casing. In the

form shown, the valve 5 is provided with laterally projecting end flanges 8 and 9 and an intermediate flange 10 which snugly fit the walls of the valve casing to divide the bore thereof into the admission chamber 6 60 and the exhaust chamber 7, which are closed at their ends. While this is the preferred construction, the flanges could be formed upon the valve casing and fitted to the body of the valve. The flanges 8 and 10 forming 65 the admission chamber 6 are preferably arranged closely adjacent each other and the valve casing is provided in its side wall with an inlet port 11 and a series of exhaust ports 12 opening respectively into the inlet and 70 exhaust chambers 6 and 7. The inlet port 11 extends through a nozzle 14 to which the supply pipe 15 may be connected. The exhaust ports 12 communicate with a passage 16 extending through the abutment 3 75 on the cylinder. This portion of the abutment terminates in a flange 17 to which an exhaust pipe may be coupled.

The bore of the valve casing is preferably provided with a steel bushing 18 and the 80 bore and bushing are preferably slightly tapered so that the latter may be snugly fitted within the valve casing. The smaller end of the bore of the valve casing is preferably arranged lowermost when the valve is disposed in vertical position, as shown in the drawings. The flanges 8, 9 and 10 of the valve 5 are also preferably ground into the bushing 18 with a slight taper fit, the smallest portion of the taper being at the lower end 85 of the valve. The bushing 18 is of course provided with openings corresponding to the inlet and exhaust ports 11 and 12 in the main body of the valve casing.

The valve 5 is provided with a central 95 bore 19 which is closed at its ends. The bore or opening 19 extends on opposite sides of the flange 10 between the inlet and exhaust chambers 6 and 7 and communicates with one of these chambers, while the 100 valve is provided in the other of the chambers with a ported wing or wings which control a port or ports in the side wall of the valve casing. In the form shown, the valve is provided with a series of ports 20 105 in its side wall communicating with the bore 19 and opening into the admission chamber 6. In the exhaust chamber, the valve shown in the drawings, is provided with two radial wings 21 which snugly fit 110

the wall of the valve chamber. These wings are arranged between the flanges 9 and 10 but terminate short of the flanges so as to leave the spaces or passages 22 between the flanges 9 and 10 and the ends of the wings 21. The wings 21 are provided with a series of radial ports 23 which communicate with the central bore 19 of the valve and the valve casing is provided in the form shown, 10 with two ports 24 which are controlled by the wings 21 of the valve as the latter is rotated or oscillated. By shifting the valve the ports 24 may be placed either in communication with the central bore 19 of the valve or with the exhaust ports 12 of the valve casing. The central bore 19 is of course always in communication through the ports 20 with the inlet port 11 of the valve casing. In the form shown, the ports 24 of the valve casing communicate with the ports or passages 25 in the wall of the engine cylinder and which lead respectively to the opposite ends of the cylinder. In the normal, central position of the valve the 25 ports 24 are both closed by the wings 21 of the valve. By oscillating the valve in opposite directions the opposite ends of the cylinder may be placed alternately in communication with the inlet and exhaust so that the flow of fluid under pressure to the engine cylinder may be readily controlled by hand to effect the reciprocation of the piston in the cylinder and parts operated thereby.

30 It will be noted that the valve is perfectly balanced both on the admission and exhaust side. The inlet pressure is exerted upon the opposite closed ends of the central bore 19 and upon the opposed flanges 8 and 9 which form the closed ends of the inlet chamber 6, so that the inlet pressure is balanced in axial direction. Moreover, the arrangement of the ports 20 and 23 is such that the inlet pressure is entirely balanced 40 in radial direction. The exhaust pressure is exerted upon the opposed flanges 9 and 10 and is therefore balanced in axial direction. By forming the spaces or passages 22 between the wings 21 and the flanges 9 and 10, the exhaust pressure is exerted on both 50 sides of the valve and is balanced in radial direction. The valve may therefore be very readily shifted by hand. The construction is also such as to obviate the necessity of 55 employing heads upon the ends of the valve casing and also does away with packing rings, stuffing boxes and the like. It should also be noted that the fluid under pressure could be admitted on either side of the 60 valve. That is to say, in the form shown for example, instead of admitting the fluid under pressure through the port 11 and exhausting it through the ports 12 and the passage 16, it could be admitted to the passage 16 and ports 12 and exhausted through

the central bore 19 and ports 20 and 11, and in either case the valve would be perfectly balanced. The present form of valve shown could be employed either as a one, two, three or four-way valve, or by increasing 70 the number of wings it could control a large number of ports. The improved valve may of course, be used with air, gas, steam or any suitable liquid under pressure and may be applied to any ordinary form of engine 75 cylinder. It would be particularly useful for controlling the flow of fluid between the high and low pressure cylinders of a compound engine.

80 While the valve may be used in any position, either horizontal or vertical or at an incline, it is preferably employed in a vertical position, as shown. When so arranged in vertical position, the valve is preferably provided with a center bearing at its lower 85 end comprising a stud 26 threaded through a cross bar or bridge piece 27 that is secured at its ends to the valve casing 1 by bolts 28. The stud is adjustably locked in position by a nut 29 and engages a plug 30 in the end 90 of the valve. A stem 31 threaded into the opposite end of the valve is provided with a suitable crank or lever for operating it. When the valve is arranged in horizontal position, journal studs are threaded into the 95 opposite ends thereof and mounted in suitable bearings.

99 In the form of hand-operated valve shown, a spring is provided for holding the valve in normal, central position with the 100 wings 21 closing the ports 24. This spring 32 is U-shaped as shown, and is coiled at its central portion about a stud 33 fixed to the end flange 9 of the valve at one side of the center thereof. The leg portions of the 105 spring engage studs 34 fixed to the flange 9 to one side of the center thereof and opposite the stud 33 and the extreme curved ends of the leg portions of the spring engage a pair of studs 35 fixed to the valve casing. 110 It is obvious that when the valve is shifted in either direction from normal, central position, the spring 32 will be placed under tension and will tend to return the valve to 115 normal position and close the ports 24.

115 It is obvious that numerous changes may be made in the details set forth without departure from the essentials of the invention.

Having described the invention, what I 120 claim as new and desire to secure by Letters Patent, is:—

125 1. A valve for controlling the flow of fluid under pressure, comprising a casing having a valve chamber closed at its ends and a rotary valve axially arranged in said chamber, said valve having a central bore and radial wings fitting the wall of said chamber and terminating short of the ends thereof whereby the pressure on opposite 130

sides of said wings is balanced, said wings having ports communicating with the central bore of the valve, and said casing having ports in its side wall controlled by said wings.

5 2. A valve for controlling the flow of fluid under pressure, comprising a casing having a cylindrical valve chamber closed at its ends and a rotary valve axially arranged in said chamber, said valve having a central bore and a series of uniformly disposed, radial wings fitting the cylindrical wall of said chamber and terminating short of the ends thereof whereby the pressure on 10 the opposite sides of said wings is balanced, said wings having ports communicating with the central bore of the valve and said casing having ports in its side wall controlled by said wings and a port in its side 15 wall opening into the chamber about the valve.

20 3. A valve for controlling the flow of fluid under pressure, comprising a valve casing and a rotary valve axially arranged in said casing, one of said parts having flanges fitting the other and forming a chamber closed at its ends, said valve having a central bore and a number of uniformly disposed radial wings fitting the 25 wall of said chamber and terminating short of said flanges, said wings being provided with ports communicating with the central bore of the valve, and said valve casing having ports in its side wall controlled by 30 said wing or wings.

35 4. A valve for controlling the flow of fluid under pressure, comprising a valve casing having an open-ended, cylindrical bore and a rotary valve axially arranged 40 therein, having a central bore and flanges fitting the cylindrical bore of said casing and forming closing end walls therefor, said valve being provided with a wing or wings intermediate said flanges and fitting 45 the wall of said casing, said wing or wings having ports communicating with the bore of said valve, and said casing having ports controlled by said wing or wings.

50 5. A valve for controlling the flow of fluid under pressure, comprising a valve casing having a cylindrical bore and a rotary valve axially arranged in said casing and having a central bore and flanges fitting said casing, said valve having a number 55 of uniformly disposed radial wings arranged between and terminating short of said flanges and fitting the wall of said casing, said wings having ports communicating with the bore of the valve, and said 60 casing having a port or ports in its side wall controlled by said valve and a port in its side wall opening into a space about the valve.

65 6. A valve for controlling the flow of fluid under pressure, comprising a valve

casing having inlet and exhaust chambers and a rotary valve axially arranged in said casing, said valve having a central bore communicating with one of the chambers of the valve casing and a radial wing in the 70 other chamber fitting the wall of the valve casing, said wing having a port communicating with the bore of the valve and said valve casing having a port or ports controlled by said wing.

75 7. A valve for controlling the flow of fluid under pressure, comprising a valve casing having a cylindrical bore divided to form inlet and exhaust chambers closed at their ends and ports in the side wall of said 80 casing opening into said chambers and a rotary valve axially arranged in the bore of said casing, said valve having a central bore closed at its ends and communicating with one of said chambers, and said valve having a series of uniformly disposed, radial wings in the other of said chambers, said wings fitting the wall of the chamber and terminating short of the ends thereof and having ports communicating with the bore 85 of the valve, and said casing having ports in its side wall controlled by said wings.

90 8. A valve for controlling the flow of fluid under pressure, comprising a casing having a cylindrical bore and a rotary valve 95 axially arranged in the bore of said casing, one of said parts having flanges fitting the other of said parts and forming inlet and exhaust chambers closed at their ends, said valve having a central bore communicating 100 with one of said chambers and having a radially disposed wing or wings in the other of said chambers fitting the wall thereof, said wing or wings having ports communicating with the bore of said valve and said 105 casing having ports in its side wall controlled by said wing or wings and having inlet and exhaust ports opening into the chambers about the valve.

110 9. A valve for controlling the flow of fluid under pressure, comprising a valve casing having a cylindrical bore, a rotary valve axially arranged in the bore of said casing, one of said parts having flanges fitting the other and forming inlet and exhaust chambers closed at their ends, said valve casing having inlet and exhaust ports opening into said chambers and said valve having a central bore closed at its ends and communicating with one of said chambers 115 and said valve having a series of uniformly disposed, radial wings in the other of said chambers fitting the wall thereof and terminating short of its ends, said wings having ports communicating with the bore of 120 the valve and said casing having ports in its side wall controlled by said wings.

125 10. A valve for controlling the flow of fluid under pressure, comprising a casing having a cylindrical bore and a rotary 130

valve axially arranged therein having a central bore closed at its ends and provided with end flanges and an intermediate flange fitting the bore of said valve casing and forming inlet and exhaust chambers, said valve having ports in its side wall communicating with one of said chambers and radial wings arranged in the other of said chambers and fitting the wall thereof, said wings being arranged between one of said end flanges and said intermediate flange and terminating short of said flanges and having ports communicating with the central bore of the valve, said valve casing having ports in its side wall, certain of said ports being controlled by said wings and certain of said ports opening into said inlet and exhaust chambers.

11. A valve for controlling the flow of fluid under pressure, comprising a valve casing and a rotary valve axially arranged in said casing, one of said parts having end flanges and an intermediate flange fitting the other of said parts and forming inlet and exhaust chambers closed at their ends, said valve casing having inlet and exhaust ports in its side wall opening respectively into said chambers, said valve having a central bore, ports in its side wall leading from said bore into one of said chambers and a series of radial wings in the other of said chambers fitting the wall of said casing, said wings being arranged between two of said flanges and terminating short of the

flanges and having ports communicating 35 with the central bore of the valve, said valve casing having ports in its side wall controlled by said wings and a spring for holding said valve in central position.

12. A valve for controlling the flow of fluid under pressure, comprising a valve casing having a cylindrical bore, a rotary valve axially arranged in the bore of said casing and provided with end flanges and an intermediate flange, said flanges having 40 a taper fit with the bore of said valve casing and forming inlet and exhaust chambers closed at their ends and a center bearing for said valve, said valve casing having ports in its side wall opening into said inlet and 45 exhaust chambers and said valve having a central bore closed at its ends and ports in its side wall leading from the central bore to one of said chambers, said valve having also radial wings in the other of said chambers fitting the walls thereof and terminating 50 short of its ends, said wings having ports communicating with the bore of the valve and being arranged to control certain 55 of the ports in the side wall of the valve 60 casing.

JOHN F. DEVINE,
Administrator of the estate of Edward T.
Slough, deceased.
